WIRE CLIP FOR INGOT MOLD SIDEBOARD
 Sherwood G. Haw, R.D. 1, Magnolia, Ohio
 Filed Apr. 5, 1963, Ser. No. 270,928
 1 Claim. (Cl. 24—261)

This invention relates to hot top means for ingot molds and more particularly it pertains to a wire clip for securing heat insulating sideboards to the inner surfaces of an ingot mold.

A sideboard is attached to each opposite side surface at the upper end of an ingot mold to maintain a reservoir of hot metal in the upper end portion of the mold during solidification of the lower portion of the ingot. The sideboards may be composed of an insulation material to reduce the escape of heat from the molten metal through the side walls of the mold, or the sideboard may be composed of an exothermic material. Such sideboards are frequently preferred because they are a relatively inexpensive addition to the cost of manufacture which adds greatly to the yield of an ingot.

A problem associated with the use of sideboards has been the provision of adequate means for mounting and holding the sideboards in place. Various devices have been used, but more recently wire clips have been adopted for attaching and holding the sideboards in place.

A difficulty with most wire clips used heretofore has been simply that they have not been satisfactory for holding the sideboards against the surface of the mold when the buoyancy of the liquid metal lifts the sideboard up and out of the mold.

The primary disadvantage of using a clip of such prior construction has been that during the pouring of an ingot it became necessary to slow down or even stop as the molten metal rises to and contacts the bottom of the sideboard to permit solidification of the steel at the bottom edge of the sideboard. Subsequent continued pouring may be done then without the buoyant effect of the metal lifting the sideboard. The disadvantage of such hesitation or stopping is that the slag or other nonmetallic inclusions are poured into the body of the ingot when the pouring is begun again.

It has been found that a clip composed of wire-like members may be provided which overcomes the prior art difficulties by providing an inturned end portion which bites into the side of the mold and holds the sideboards in place. The clips of prior construction have not been satisfactory for that purpose.

Accordingly, it is an object of this invention to provide a wire clip for ingot mold sideboards having a configuration which operates against vertical lifting forces such as the buoyant effects of the metal.

It is another object of this invention to provide a wire clip for ingot mold sideboards which holds the sideboards with sufficient lateral force to cause greater than usual surface friction between the sideboards and the surface of the mold.

Finally, it is an object of this invention to provide a wire clip for ingot mold sideboards which substantially eliminates the difficulties enumerated and obtains the foregoing desiderata in an effective manner.

These and other objects and advantages, apparent to those skilled in the art from the following description and claims, may be obtained, the stated results achieved, and the described difficulties overcome, by the apparatus, combinations, parts, elements, subcombinations, arrangements, and constructions which comprise the present invention, the nature of which is set forth in the following general statement, a preferred embodiment of which—illustrative of the best mode in which applicant has contemplated applying the principles—is set forth in

2

the following description and shown in the drawing, and which are particularly and distinctly pointed out and set forth in the appended claim forming part hereof.

The improved wire clip of the present invention may be stated in general terms as including an elongated wire-like member having an intermediate straight portion and downturned end portions, one downturned end portion being inclined at an angle of 103° to the intermediate portion and having a lower curved extremity which is upturned at an angle of 46° to the vertical and is directed toward the intermediate portion, the other downturned end portion forming an eye extending above the intermediate portion and being inclined from a position above to a position below the intermediate portion, and at an angle of 60° to the intermediate portion, and said eye operating as a spring member for urging said other end portion toward said one end portion.

Referring to the drawing in which a preferred embodiment is shown by way of example:

FIGURE 1 is an isometric view with portions broken away, showing the manner in which wire clips of the present invention are used to hold sideboards in place against the inner wall of an ingot mold;

FIG. 2 is an enlarged sectional view taken on the line 2—2 of FIG. 1; and

FIG. 3 is an enlarged elevational view showing the wire clip in condition prior to use.

Similar numerals refer to similar parts throughout the several views of the drawing.

In FIG. 1 a mold is generally indicated at 1 and is preferably of the big-end-down type of mold construction. A pair of sideboards 2 and 3 are mounted on opposite inner surfaces 4 and 5 of the mold where they are held in place by clips 6.

The sideboards 2 and 3 are usually attached to the inner surfaces of a mold as shown in order to reduce the amount of heat escaping from the ingot during its solidification in the mold. For that purpose the sideboards 2 and 3 may be composed of insulation material.

The sideboards may also be composed of exothermic material which fuses upon contact with the molten ingot metal for supplying heat to the reservoir of molten metal at the upper end of the mold. Inasmuch as the composition of the sideboards 2 and 3, whether composed solely of insulation material or exothermic material or a combination of both, is lighter than molten metal surrounding it in the mold, there has been a tendency for the sideboards to rise out of their position due to the buoyancy of the liquid metal which defeats the purpose of the sideboard.

The clips 6 are preferably composed of rod or wire-like material such as type 1065-C or equivalent spring steel. For most ingot molds, the diameter of the material is $\frac{5}{16}$ " round. However, larger diameters may be used where longer clips are required for larger ingot molds. The clip 6 is preferably fabricated from a single elongated segment of steel wire into the configuration shown in FIG. 3 which includes an elongated intermediate portion 7, one end portion 8, and another end portion 9. The intermediate portion 7 may vary in length from 8 to 18" depending upon the thickness of the wall of the mold 1. The end portion 8 extends downwardly from the intermediate portion at an angle slightly greater than 90° and preferably at an angle of 103°. The lower extremity includes a rounded portion 10 and an upturned member 11 which extends preferably at an angle of 46° from a horizontal plane. The radius of curvature of the arc between the portions 7 and 8 as well as the rounded portion 10 is preferably 1".

The other end portion 9 likewise extends downwardly from the intermediate portion 7 and preferably at an

angle of 60° thereto. The portions 8 and 9 are interconnected by an upturned loop or eye 12 having the preferred radius of curvature of 1". The loop 12 holds the end portion 9 at the preferred angle of 60° and inclined at an angle substantially parallel to the other end portion 8.

As shown in FIG. 2, when the clip 6 is attached in place the end portions 8 and 9 extend downwardly on opposite sides of the wall of the mold 1 with the intermediate portion disposed across and over the upper end of the wall. The clip 6 spans the mold and the sideboard and holds the end portion 9 out of its natural position or angle with the intermediate portion 7. The sharp corner of the upturned member 11 engages or bites into the outer surface of the mold wall. As a result of the tensional forces created between the portions 8 and 9, the clip 6 holds the sideboard 2 tightly in place against the inner surface 4 of the wall of the mold 1. Accordingly, the compression on the sideboard is sufficient to more than offset any buoyant effect of the molten metal as it rises above and around the sideboards 2 and 3.

Due to the spacing between the outer surface of the mold and the end portion 8, it is relatively easy to install the clips 6 in place, because the spacing is sufficiently large for insertion of the fingers of a person attaching the clips in place. The tension created between the end portions 8 and 9 is at least ten times greater than the tension created between the end portions of wire clips of prior construction. The arrow 13 shows the direction of tensional forces applied by the end portion 9 against the sideboard 2. It is sufficient to hold the sideboard tightly in place.

Any effort to raise the sideboard out of place is defeated by a sharp corner 14 of the upturned member 11 biting into the mold wall surface. As a result of the foregoing, where it is necessary to remove the clip 6 for any reason prior to pouring of molten metal into the mold 1, the end portion 8 must first be pulled to disengage the corner 14 from the surface of the mold. Any other attempt to remove the clip, aside from the application of excessive force, is substantially ineffective.

The device of the present invention provides a wire-like clip for holding and maintaining sideboards in place against the inner surface of an ingot mold. The clip is an improvement over clips of prior construction because it is designed to apply great lateral force on the sideboard to hold it in place against the inner mold wall. The clip, having another end portion which bites into the mold wall, is effective in overcoming any attempt to lift the sideboard vertically out of the posi-

tion in which it is placed. As a result, the wire clip of the present invention constitutes a greater improvement over clips of prior construction and satisfies a great need in the art.

In the foregoing description certain terms have been used for brevity, clearness, and understanding, but no unnecessary limitations are to be implied therefrom as such words are used for descriptive purposes and are intended to be broadly construed.

Moreover, the embodiment of the improved construction illustrated and described herein is by way of example and the scope of the present invention is not limited to the exact construction shown.

Having now described the invention, construction, operation and use of a preferred embodiment thereof and the advantageous, new, and useful results obtained thereby; the new and useful wire clip for ingot mold sideboard and reasonable mechanical equivalents thereof obvious to those skilled in the art are set forth in the appended claim.

What is claimed is:

A wire clip for attaching a sideboard to the inner surface of an ingot mold including an elongated wire composed of resilient material such as spring steel and having an intermediate straight portion and having down-turned end portions, one downturned end portion being outwardly inclined at an angle to the intermediate portion and having an inturned lower curved extremity of substantial length and terminates in a free end which extends beyond the connection of said one downturned end portion with said intermediate straight portion and has a sharp straight edge thereon which is directed toward the intermediate portion, the other downturned end portion forming a loop extending above the intermediate portion and being inclined from a position above to a position below the intermediate portion, said other end portion being substantially parallel to said one end portion, said loop operating as a spring means for urging said other end portion toward said one end portion and the spring means when the clip is in use also urging said sharp edge into biting engagement with an associated ingot mold.
